**COMBUSTION CHAMBER WITH
FUEL VAPORIZER**

Floyd G. Dougherty, Indianapolis, Ind., assignor to General Motors Corporation, Detroit, Mich., a corporation of Delaware

Application December 15, 1950, Serial No. 200,965

7 Claims. (Cl. 60—39.71)

My invention relates to combustion apparatus, particularly to combustion chambers for gas turbine engines. The primary object of the invention is to improve combustion in such engines, especially aircraft engines which operate at high altitudes.

Maintenance of proper combustion conditions in aircraft gas turbines is difficult, but great progress has been made in this respect in recent years. At sea level or low altitudes, with fairly volatile fuels, no great difficulty is now experienced. It is found, however, that combustion becomes more critical as altitude is increased, until ultimately an altitude is attained at which combustion cannot be consistently maintained. Also, reignition of the flame is usually impossible through a considerable altitude range immediately below the ceiling.

The highest possible ceiling, and good performance up to the ceiling, are important requirements in certain types of aircraft.

My invention is adapted to increase the operational ceilings of gas turbine engines by several thousand feet, to provide more consistent performance, and to permit the elimination of high pressure fuel systems and liquid fuel spray nozzles with their attendant shortcomings.

Other advantages of the invention are that it makes possible the use of shorter burners, thus permitting a reduction in the length and weight of the engine; improves combustion efficiency as a result of better fuel-air mixing and better temperature distribution in the burner; lessens pressure drop in the combustion section; and improves ignition and blowout characteristics.

The invention involves a novel arrangement for introduction of air for combustion and mixing of fuel in a vaporized condition with the air in connection with a fuel vaporizer in each combustion chamber where liquid fuel is used.

Many ignition and combustion problems arising from jet engine burner development are directly related to the inability of the burner to consume liquid fuels most effectively. When the fuel is admitted in the form of a spray, as with the conventional spray nozzle, the fuel must first be broken into fine particles, distributed throughout the combustion chamber, heated, vaporized, and mixed with air before ignition and combustion can occur. This not only creates a time lag in the ignition sequence, but also requires the fuel to be introduced under unduly high pressure. This necessitates burner designs that purposely promote turbulence and pressure losses that are detrimental to overall engine performance.

The principal objects of the invention are to improve combustion in gas turbine engines, to improve high-altitude performance, to facilitate the use of less volatile fuels than are now preferred, to provide an improved combustion chamber, to provide a more satisfactory fuel system, and to provide an improved vaporizer and fuel injection apparatus.

The appended detailed description of the preferred embodiment of the invention will make clear to those skilled in the art the advantages of the invention and the preferred manner in which the objects are realized.

2

Referring to the drawings: Figure 1 is a partial longitudinal sectional view of a gas turbine combustion chamber incorporating the invention, and Figures 2 and 3 are partial cross-sectional views taken on the planes indicated in Figure 1.

In the interest of conciseness, I refrain from illustrating or describing a gas turbine engine as a whole, since such engines are well known to those skilled in the art, and the details of the turbine, the compressor, various auxiliary components, and the organization thereof into an engine are immaterial to my invention. Since the invention may be employed in combustion chambers of varying structure, I have shown only so much of an illustrative combustion apparatus as is requisite to make the invention clear to those skilled in the art.

In Figure 1, the diffuser 11 of the compressor of a gas turbine engine is represented as bounded by inner and outer walls 12 and 13. This passage may be annular, as is customary with axial-flow compressors, or may be one of a plurality of outlets of a radial-flow compressor. If the diffuser is for an axial-flow compressor, it is ordinarily divided by radial partitions into a number of individual outlets arranged circumferentially around the axis of the compressor shaft. At each outlet of the diffuser a flanged ring 14 is mounted. The ring 14 constitutes a pilot for a ring 16 fixed to the forward end of a generally cylindrical sheet metal shell 17 which constitutes a combustion chamber of the engine. The combustion chamber 17 is assembled to the diffuser by a ring clamp 18 of known type. Mounted within the combustion chamber 17 is a flame stabilizing device, specifically a generally cylindrical flame tube 19 within which the actual combustion and dilution of the combustion products take place. Air from the compressor is circulated through a space between the walls 17 and 19 and the major part of this secondary air enters the flame tube through openings in the wall thereof, as is well known.

Only the forward end of the combustion chamber 17 and the flame tube 19 are illustrated, since the details of these structures are immaterial to the invention and they may follow well-known principles of design. The outlets of the flame tubes 19 discharge into the turbine in the usual manner. The downstream end of the diffusing passage 11 constitutes the forward part of the combustion chamber, which is continued in the chamber 17. The upstream section or entrance cone of the flame tube is constituted by a generally conical or diverging shell 22 of heat resistant sheet metal which may be supported in the diffuser by a plurality of legs 23 secured to a flange of the diffuser by studs 24 and nuts. The downstream end of the entrance cone 22 enters within the upstream end of the flame tube 19, which is ribbed as indicated at 26 to secure a bearing between the two members and to provide inlets 27 for cooling air distributed around the circumference. A machine screw 28, threaded into a boss at the forward end of the shell 19, is piloted in a hole in the entrance cone 22 to prevent separation of the parts 19 and 22. A slightly tapering sleeve or inner cone 31 is mounted within the nose of the outer cone 22 and fixed thereto by four clips 32 welded to the two cones. This arrangement provides an annular air inlet 33 to the nose of the combustion cone 22 and a second air inlet through the interior of the cone 31. The primary combustion air enters through the annular opening 33 and cooling air through the tube 31. Additional cooling air may enter through openings in the flame tube 19, as is customary.

Liquid fuel for combustion is supplied from any suitable regulated source (not shown) through a conduit 36 which is connected by standard tube fittings 37 to a tube 38 entering the diffuser and passing rearwardly through the inner cone 31. The fittings 37 may be mounted on a

plate 39 fixed to the outer wall 13 of the diffuser by cap screws 41.

The tube 38 continues into a vaporizing coil 42 composed of a number of turns of the tube in a generally helical arrangement disposed around the inner cone 31. As will be noted, the individual coils 42 vary in coil diameter in a generally staggered arrangement so that they are most effectively exposed to the gases flowing longitudinally of the combustion apparatus for best heat transfer.

The forward end of the vaporizing coil 42 continues into a tubular ring fuel injection manifold 44 concentric with the cones 22 and 31 and located a short distance downstream from the air inlet 33. The ring 44 is guided and supported on the inner cone 31 by a plurality of fingers 46 welded to the manifold 44. A large number of small fuel injection holes 47 are drilled in the upstream face of the manifold ring 44. The size and number of these holes will, of course, depend upon the fuel requirements of the combustion chamber.

The entrance cone 22 is provided with an outwardly extending tube 48, which may be welded thereto, into which projects the discharge end of a torch igniter 50. The igniter may be supported by a plate 51 bolted to the outer wall 13. Torch igniters are well known, and the details of the igniter are immaterial to the invention, and are therefore not illustrated. The igniter comprises a fuel spray nozzle or gas jet with means for igniting the fuel and means providing a supply of air under pressure to provide a jet of flame into the combustion chamber. The outlet of the jet igniter is adjacent the coil 42 so that the igniter heats the vaporizer.

In operation, the auxiliary fuel supply to the igniter 50 is activated and the ignition is energized to provide a flame jet. When the coil 42 has been heated, liquid fuel is introduced through the tube 38, is vaporized in the coil 42, and injected into the air stream through the orifices 47. The fuel mixes with the air entering through the annular opening 33 and the mixture is ignited by the torch flame.

The fuel from the manifold 44 burns over the vaporizer 42, heating and vaporizing the fuel passing through, and the igniter may be shut off. Since the fuel is in vapor form as it enters the air stream, combustion takes place immediately after injection without the delay necessary for vaporization of atomized liquid in the air stream.

Relatively heavy or non-volatile fuels may be employed, since vaporization is effected before injection. The high pressures required for effective atomization of liquid fuel are not required with the vapor injection system. A pressure of not more than fifty pounds per square inch above that in the combustion chamber is sufficient.

The torch igniter may be dispensed with, if desired, by feeding a gas such as butane or propane, which may be readily ignited by a spark without preheating or vaporization through the tube 38, and using the flame from the manifold 44 to heat the vaporizer. When the vaporizer is thus heated, the liquid fuel may be fed through the lines 36 and 38.

Since the fuel is injected at the extreme forward end of the flame tube assembly, injected upstream, and in vapor form, burning takes place at the forward end of the combustion space instead of well downstream as with conventional fluid-spray combustion chambers. The combustion apparatus may therefore be decreased in length.

About one-third of the total air is admitted directly through the opening 33 and the inner cone 31, thus providing for a low total pressure drop as compared to combustion chambers in which only a relatively small part of the air is admitted at the entrance cone of the flame tube.

The vaporization of the fuel is particularly helpful at extreme altitudes where the density of the air in the

combustion chamber is low and maintenance of combustion difficult.

It will be apparent to those skilled in the art from the foregoing description that the invention possesses many advantages, and that these advantages may be retained in whole or in part notwithstanding variations in structure of the apparatus employed to effectuate the principles of the invention.

The invention is not to be considered as limited or restricted by the detailed description of the preferred embodiment thereof.

In this connection, it may be noted, for example, that the structure shown, with the vaporizing coil eliminated, is particularly suited for combustion of gaseous fuel. Also, the structure may be readily modified for application to annular combustion casings with annular flame tubes or flame holders therein, while retaining the principles of the invention. Obviously, the invention is applicable to fuel burners which receive the gases discharged from a turbine rather than from a compressor, as in reheat burners and afterburners for jet engines.

In certain cases, particularly in afterburners, the flame tube downstream of the entrance portion may be omitted, and the entrance portion may serve as a flame holder.

I claim:

1. A combustion apparatus comprising, in combination, in combustion chamber structure defining an air passage with an inlet and an outlet, a flame stabilizing device therein including means defining an inlet for primary combustion air at the upstream end of the flame stabilizing device and means defining an entrance into the flame stabilizing device for additional air downstream from the said inlet, the flame stabilizing device portion extending from the said inlet to the said entrance increasing in cross section downstream, a fuel manifold disposed within the said portion with orifices therein for discharge of fuel into the flame stabilizing device, a fuel heating coil disposed within said portion downstream from the manifold and discharging into the manifold, and means for supplying fuel to the heating coil.

2. A combustion apparatus comprising, in combination, a combustion chamber structure defining an air passage with an inlet and an outlet, a flame stabilizing device therein including means defining an inlet for primary combustion air at the upstream end of the flame stabilizing device and means defining an entrance into the flame stabilizing device for additional air downstream from the said inlet, the flame stabilizing device portion extending from the said inlet to the said entrance increasing in cross section downstream, a fuel manifold disposed within the said portion immediately downstream from the inlet with orifices therein for discharge of fuel into the flame stabilizing device, a fuel heating coil disposed within said portion downstream from the manifold and discharging into the manifold, and means for supplying fuel to the heating coil.

3. A combustion apparatus comprising, in combination, a combustion chamber structure defining an air passage with an inlet and an outlet, a flame stabilizing device therein including means defining an annular inlet for primary combustion air at the upstream end of the flame stabilizing device and means defining an entrance into the flame stabilizing device for additional air downstream from the said inlet, the flame stabilizing device portion extending from the said inlet to the said entrance increasing in cross section downstream, a tubular ring fuel manifold disposed within the said portion adjacent the inlet with orifices therein for discharge of fuel into the flame stabilizing device, a fuel heating coil disposed within said portion downstream from the manifold and discharging into the manifold, and means for supplying fuel to the heating coil.

4. A combustion apparatus comprising, in combina-

tion, a combustion chamber structure defining an air passage with an inlet and an outlet, a flame tube therein comprising an entrance portion with a first air inlet at the end thereof toward the combustion chamber air inlet, a sleeve within the first inlet extending downstream and defining a second air inlet, a tubular ring fuel injection manifold disposed around the sleeve adjacent the first air inlet with orifices formed therein for discharge of fuel, and means for supplying gaseous fuel to the manifold.

5. A combustion apparatus comprising, in combination, a combustion chamber structure defining an air passage with an inlet and an outlet, a flame tube therein comprising an entrance portion with a first air inlet at the end thereof toward the combustion chamber air inlet, a sleeve within the first inlet extending downstream and defining a second air inlet, a tubular ring fuel injection manifold disposed around the sleeve adjacent the first air inlet with orifices formed therein for discharge of fuel, a fuel heating coil arranged around the sleeve downstream from the manifold and discharging into the manifold, and means for supplying fuel to the heating coil.

6. A combustion apparatus comprising, in combination, a combustion chamber structure defining an air passage with an inlet and an outlet, a flame tube therein comprising an entrance portion with a first air inlet at the end thereof toward the combustion chamber air inlet, a sleeve within the first inlet extending downstream and defining a second air inlet, a tubular ring fuel injection manifold disposed around the sleeve adjacent the first

air inlet with orifices formed therein for discharge of fuel, a fuel vaporizing coil arranged around the sleeve downstream from the manifold and discharging into the manifold, means for supplying fuel to the vaporizing coil, and pilot flame fuel ignition means adapted to heat the coil.

7. A combustion apparatus comprising, in combination, a combustion chamber structure defining an air passage with an inlet and an outlet, a flame tube therein comprising an entrance portion with an inlet for primary combustion air at the end thereof toward the combustion chamber air inlet, a sleeve within the said inlet extending downstream and defining an inlet for cooling air, a tubular ring fuel injection manifold disposed around the sleeve adjacent the primary combustion air inlet with orifices formed therein for discharge of fuel, a fuel heating coil arranged around the sleeve downstream from the manifold and discharging into the manifold, and a fuel supply line connected to the heating coil extending into the flame tube through the said sleeve.
